UNITED STATES PATENT OFFICE

162,493

FILE CABINET

Ernest Frederick Thomson, Tuckahoe, N. Y., assignor to The Globe-Wernicke Co., Norwood, Ohio, a corporation of Ohio

Application October 29, 1949, Serial No. 5,789

Term of patent 7 years

(Cl. D33—19)

To all whom it may concern:

Be it known that I, Ernest Frederick Thomson, a citizen of Canada, residing at Tuckahoe, in the county of Westchester and State of New York, have invented a certain new, original, and ornamental Design for a File Cabinet, of which the following is a specification, reference being had to the accompanying drawing, forming a part hereof.

The drawing shows a perspective view of a file cabinet embodying the design.

I claim:

The ornamental design for a file cabinet, substantially as shown.

ERNEST FREDERICK THOMSON.
